HEAT REGULATION

Grant M. Richard, Toledo, Ohio

Application February 3, 1933, Serial No. 655,018

5 Claims. (Cl. 236—16)

This invention relates to temperature responsive control mechanism.

This invention has utility when incorporated in readily detachable thermo-responsive controllers for hot air furnaces.

Referring to the drawing:

Fig. 1 is a view of an embodiment of the invention in a hot air furnace installation as for residence heating, parts being broken away;

Fig. 2 is a detail view in plan, of the housing for the control unit or regulator;

Fig. 3 is an enlarged side view of the adjusting arm for the regulator;

Fig. 4 is a plan view of the regulator with the upper housing portion broken away;

Fig. 5 is a view on the line V—V, Fig. 4;

Fig. 6 is a fragmentary view showing the reversing switch from the line VI—VI, Fig. 4; and

Fig. 7 is an additional detail view of the reversing switch from the line VII—VII, Fig. 6.

Hot air furnace 1, say as located in the basement of a dwelling, may be equipped with fire door 2 and ash door 3 having adjustable section 4 as a damper. This hot air furnace 1 is shown as having heat dome 5 with pocket 6 as a holder for heat retaining medium, say of sand 7. From this dome 5, ducts 8 extend to various parts of the dwelling to be heated. From the fire portion in the furnace to which access is obtained by the fire door 2, products of combustion are taken off by flue 9 having riser section 10 and check draft 11. Connected from this check draft 11 to the damper 4 is flexible line or chain 12 passing about guide rollers 13.

In carrying out the invention herein, thermo-responsive operation is effective for opening the check draft 11 as the damper 4 is closed in one direction of movement of the connection 12. In the reverse direction movement of the connection 12 there is closing of the check draft 11 and opening of the draft damper 4 so that the heating operation of the furnace may be accelerated. This operation of the connecting chain 12 is herein brought about by connection 14 with pulley 15 on arm 16 having adjustable clamp connection 17 with protruding shaft portion 18 from the housing 19.

This housing 19 is shown as having from the lower portion thereof pocket 20, in which is anchored by bolt 21 a bimetallic thermo-responsive strap 22 extending through opening 23 into the housing 19 from the pocket 20. It is thus seen that this pocket 20 may be embedded in the sand 7 or brought into such proximity to the dome 5 as to check readily the temperature changes

therein as such tend to flex the bimetallic element 22.

The regulator herein is one which, as shown, may be readily installed with no alteration whatsoever in the furnace installation or equipment. The operative connection to the control chain 12 may be but a staple or loose link 14 with such desired amount of play as may be convenient for the particular installation. The drive connection is from the usual lighting circuit, say by thrusting pronged plug 24 into a socket, thereby communicating through conduit 25 with the housing 19 for electric current supply lines 26, 27, at terminals 28 in the housing 19.

The line 27 extends directly to motor 30 having shaft 31 carrying pulley 32 about which extends belt 33 to larger pulley 34 on shaft 35 as a first stage in speed reduction. This shaft 35 has thereon worm 36 in mesh with worm wheel 37 on the shaft 18 which protrudes from the housing. There is accordingly a two-stage speed reduction from the motor 30 in its one direction of rotation for operating the shaft 18.

The line 26 herein extends to terminal 38 at insulation block 39 carried by the thermo-responsive element 22 for being shifted thereby. From this terminal 38 there is conductor 40, terminal portion 41 of which is desirably magnetically-responsive as well as being a conductor. This terminal 41, as contacting terminal 42 on insulation block 43 connects circuit through line 44 to terminal 45 at insulation block 46. Mounted on this block 46 is movable terminal 47 from which extends flexible helical conductor or pig tail 48 to fixed terminal 49 at this block. From this terminal 49 extends conductor 50 to the motor 30. Accordingly, at the shifting of the arm 40 for closing of the terminals 41, 42, and with the rockable conductor 47 at the terminal 45, circuit is completed for operating the motor 30. This travel of the motor is effected for predetermined cycle, for fixed with the shaft 18 is cam 51 acting on plunger 52 mounted in bracket 53 to force such plunger 52 downward against the resistance of helical spring 54 acting on collar 55. Fixed with this plunger 52 above the collar 55 is eye 56 from which extends insulation link 57 to helical tension spring 58.

This shifting of the plunger 52 moves the eye 56 upward past fulcrum mounting 59 for the movable switch member 47, and thereby as passing, insures quick throw or snap operation away from the terminal 45 to terminal 60. This terminal 60 has therefrom conductor 61 to terminal 62 at the two-way switch arm 41, with this ter-

minal 62 corresponding to and opposing the terminal 42. The snap operation of the switch 47 opens the circuit to the motor 30 and thus causes the motor 30 to stop after 180° operation of the shaft 18.

10 As the temperature change in the dome 5 is effective to shift the arm 40 from the terminal 42 to the terminal 62, circuit is completed from the line 26 through this thermo-responsive arm 40 and the terminal 62 on the insulation block 43, thence by line 61 to the movable arm 47 of the snap cut-out, and thence by the line 50 for a re-operation of the motor 30, a second 180° movement for the arm 16. It is thus seen that from 15 one limit of swing of the arm 16 as to the chain 12, 180°, there is the full throw for this arm in effecting simultaneous opening of the check draft and closing of the ash pit damper. At the successive operation of the motor 30, the continuation 20 for a second 180° closes the check draft 11 and opens the damper 4.

25 Insulation block 43 is mounted on frame 63 in the housing 19. This insulation block 43 is provided with a pair of aligned slots 65. Screws 66 through these slots 65 engage the frame 63. The insulation block is thus held for reciprocal action in effecting the desired adjustments therefor.

30 Connected by pivot pin 64 with this insulation block 43 is link 67 having pivotal connection 68 with arm 69 of shaft 70 mounted in bracket 71 in the housing 19. This shaft 70 protrudes from the housing 19 and there has clamp connection 72 fixing pointer 73 therewith for movement over scale 74. From exterior of the housing 19 the furnace attendant may shift the pointer 73 for the desired range of temperature control as to temperature in the dome 5. This effects an adjusted location of the insulation block 43 and accordingly of the position at which the arm 40 40. may be effective for opening connection at one of the terminals and closing connection at the other of the terminals 42, 62. Beside the flexing effected by this positioning of the arm 73 there may be additional control for snap operation of 45 this arm 40 due to permanent magnets 75, 76, acting upon the magnetizable terminus 41 of the arm 40 at the respective closed positions with the terminals 42, 62.

50 To insure a balanced and smooth operation 50. of the movable terminal 47, it may be provided, on the end thereof remote from the contact points, with threaded stem 77 having counterweight 78 adjustably mounted thereon.

55 The unit shown is adapted for quick installation in the type of furnace shown. However, the various mechanical details may be changed so that the unit is easily adaptable for use on heating plants involving vapor, hot water, or steam.

60 What is claimed and it is desired to secure by Letters Patent is:

65 1. A hot air furnace having a jacket providing a heat retaining bed, a check draft, a damper, and a connection therebetween, a portable heat control unit for the furnace embodying a hous-

ing having a pocket, said unit mounted on the heat retaining bed and having the pocket extending thereinto, an arm exterior of the housing to engage the connection, mechanism interior of the housing to operate the arm, and a 5 thermostat in the pocket to control the mechanism.

2. A furnace having a jacket providing a heat retaining bed, a check draft, a damper, and a connection therebetween, a heat control unit 10 for the furnace embodying a housing having a pocket, said unit mounted on the heat retaining bed and having the pocket extending thereinto, an arm exterior of the housing to engage the connection, mechanism interior of the housing 15 to operate the arm, a thermostat in the pocket to control the mechanism, said thermostat serving as a switch arm, a bracket in the housing, a pair of contacts carried by the bracket between which the thermostat operates in control of the 20 mechanism, and means exterior of the housing to shift said contacts as to the thermostat.

25 3. A furnace having a jacket providing a heat retaining bed, a check draft, a damper, and a connection therebetween, a heat control unit for 25 the furnace embodying a housing having a pocket, said unit mounted on the heat retaining bed and having a pocket extending thereinto, an arm exterior of the housing to engage the connection, mechanism interior of the housing 30 to operate the arm, a thermostat in the pocket to control the mechanism, said thermostat serving as a switch arm, a bracket in the housing, a pair of contacts carried by the bracket between which the thermostat operates in control of the 35 mechanism, and a magnet adjacent one of the contacts insuring snap action by the thermostat with the contact.

4. A furnace having a fire box and a jacket, a check draft, a damper and a flexible mechanical 40 connection therebetween, a portable heat control unit for the furnace embodying a housing contacting the jacket for direct heat radiation thereinto, an arm exterior of the housing to engage the connection, an electric motor interior of the 45 housing to operate the arm, a pair of contacts, and a thermostat mounted in said housing to be affected by said direct heat radiation and serving as a switch arm between the contacts to control said motor.

5. A furnace having a fire box and a jacket, a check draft, a damper and a flexible mechanical connection therebetween, a portable heat control unit for the furnace embodying a housing 55 contacting the jacket for direct heat radiation thereto, an arm exterior of the housing to engage the connection, electric motor interior of the housing to operate the arm including a pair of contacts, a thermostat mounted in said housing to be affected by said direct heat radiation and serving as a switch arm between the contacts to control said motor, and means for shifting said contacts as to the thermostat.
